UNITED STATES PATENT OFFICE.

ARTHUR KATZINGER, OF CHICAGO, ILLINOIS, ASSIGNOR TO EDWARD KATZINGER COMPANY, OF CHICAGO, ILLINOIS, A CORPORATION OF ILLINOIS.

DESIGN FOR A JELLY MOLD OR SIMILAR ARTICLE.

Application filed June 4, 1926. Serial No. 17,931. Term of patent 14 years.

To all whom it may concern:

Be it known that I, ARTHUR KATZINGER, a citizen of the United States, residing at Chicago, in the county of Cook and State of Illinois, have invented a new, original, and ornamental Design for a Jelly Mold or Similar Article, reference being had to the accompanying drawings, forming a part thereof.

In the accompanying drawings—

Fig. 1 is a plan view of the exterior of a jelly mold showing my new design;

Fig. 2 is a plan view of the interior thereof; and

Fig. 3 is a perspective view thereof.

I claim:

The ornamental design for a jelly mold or similar article, as shown.

ARTHUR KATZINGER.
